TRANSFER REVOKING MECHANISM

Carl D. Brown, Hopedale, Mass., assignor to
Draper Corporation, Hopedale, Mass., a cor-
poration of Maine

Application September 25, 1940, Serial No. 358,374

9 Claims. (Cl. 139—231)

This invention pertains to automatic filling replenishing looms and more particularly relates to transfer revoking mechanism for such looms.

Looms of the above general character are now usually provided with replenishing mechanism automatically operative to replace either the bobbin or the shuttle upon substantial exhaustion of the filling carried thereby. A feeler mechanism usually detects the condition of the filling upon each alternate beat of the lay and upon detection of substantial exhaustion of filling initiates operation of the replenishing mechanism.

In addition to the above mechanisms such looms may be provided with a center filling fork mechanism for stopping the loom upon the breakage or failure of the filling. It may happen at times that the feeler mechanism will call for operation of the replenishing mechanism and during the next pick after such call the center filling fork operates to stop the loom, due to failure or breakage of the filling. In such event, the lay will be stopped before a complete transfer can be made and the shuttle or other parts of the loom may be damaged. In such cases, it is essential that the call for operation of the replenishing mechanism be revoked.

Accordingly, it is a principal object of my invention to provide in an automatic filling replenishing loom having automatic replenishing mechanism, feeler mechanism, a center fork mechanism of the type including a reciprocating member and means operated by the center fork for arresting the movement of the reciprocating member, loom stopping means, means for revoking the initiative operation of the feeler mechanism, and means carried by the reciprocating member for actuating the loom stopping means and the revoking means upon the arresting of the movement of the reciprocating member by the center fork.

The foregoing and other objects of the invention are accomplished in the construction illustrated on the accompanying drawings, of which:

Fig. 1 is a perspective view of a portion of the loom showing the feeler mechanism and the center fork mechanism, some of the parts being broken away;

Fig. 2 is a perspective view of a portion of the loom showing the replenishing mechanism;

Fig. 3 is a perspective view of a portion of the loom showing the connection between the starting rod and shuttle feeler;

Fig. 4 is a plan view of a portion of the right hand side of the loom;

Fig. 5 is a front view of a portion of the right hand side of the loom;

Fig. 6 is a fragmentary view showing the relation of the shuttle feeler and the lay; and

Fig. 7 is a fragmentary view showing the relation of the transferrer and the lay.

The particular loom shown on the drawings includes a replenishing mechanism for replacing the exhausted filling supply with a fresh supply, a feeler mechanism for feeling the filling on the bobbin to detect the condition thereof and upon detection of substantial exhaustion of filling to set in operation a train of mechanism to call for operation of the replenishing mechanism, a center fork stopping mechanism for stopping the loom upon failure or absence of filling in the shed and a transfer revoking mechanism under control of and actuated by the center fork mechanism for revoking any existing call for transfer upon the stoppage of the loom by the center fork mechanism.

The loom frame may be of the usual construction and the side frames thereof are connected by the breast beam 1 upon the left hand side of which is mounted the feeler mechanism. The feeler mechanism and the associated parts may be of any suitable character, the essential in this respect being that upon each detecting beat the feeler will detect the condition of the filling in the shuttle and when it has reached a certain degree of exhaustion will call for a change of filling. The feeler mechanism illustrated in the present instance may be of the same general type as shown and described more fully in the Brown and Repass Patent No. 1,593,426, granted July 20, 1926.

The feeler mechanism may include a stand 2 for the support of a feeler 3, and a transmitter 4 connected to a bell crank (not visible on the drawings) pivotally mounted on actuator 5. Upon the transmitter 4 being moved to the right as seen on Fig. 1, the bell crank moves into a position permitting the actuator 5 to be engaged by and slid forwardly by a cam follower (not shown). Actuator 5 is pivotally connected to an upwardly extending arm 6 fixedly secured to rocker shaft 7. The rocker shaft 7 is journaled at one end in a bracket bearing 8 on the left hand side of the breast beam (Fig. 1) and at the other end is journaled in bracket bearing 9 on the right hand side of the breast beam (Fig. 3).

Fixedly connected to shaft 7 adjacent the bracket bearing 9 is a lever 10 pivotally connected to a member 11 having a forked end for engagement with a pin 12 projecting from the shuttle

feeler 13. Shuttle feeler 13 is pivotally mounted on a stand 14 secured to the right hand loom side 15. Pivoted on shuttle feeler 13 at 16 is a latch depressor 17 engaging a projection 18 on latch 19. Latch 19 is pivotally connected to arm 20 of the transfferer 21 and is adapted when raised to operative position to engage a bunter 22 on the usual reciprocating lay 22'.

The replenishing mechanism may comprise a rotary battery indicated generally at 23, carrying a reserve supply of bobbins, a transfferer 21 and a spring 24 for normally holding the transfferer in raised position. When latch 19 is raised to operative position to call for transfer, the bunter 22 will engage latch 19 on the forward beat of the lay and move the transfferer downwardly thereby inserting a fresh bobbin in the shuttle.

The center fork mechanism and the associated parts may be of any suitable character, the essential in this respect being that upon each pick of the shuttle the fork will detect the presence or absence of filling in the shed and upon the detection of absence or failure of filling in the shed mechanism will be set in operation to stop the loom. The center fork mechanism illustrated in the present instance may be of the same general type as shown and described more fully in the Lindsjo Patent No. 1,865,930 granted July 5, 1932.

The center fork mechanism may include a bracket 25 mounted on the lay 22' substantially centrally thereof. A rocking carrier 26 to which the tines 27 of the center fork are secured is pivotally mounted on the bracket. The axis of the carrier 26 may extend to one side of the bracket as at 28 and connected with the extension 29 is a light spring 29 which serves to impart to the tines of the fork a downward movement for ascertaining whether or not filling has been laid in the shed. Slidably mounted in bracket 25 is a reciprocating rod 30 which extends longitudinally of the lay. At one end of the rod 30 is a bunter 31 as shown on Figs. 4 and 5. At the other end rod 30 is pivotally connected to a bell crank lever 32 pivotally mounted on a bracket 33 on the lay. One arm of bell crank lever 32 is provided with a bunter 34 extending forwardly therefrom as shown on Fig. 1. The other arm of the bell crank lever 32 extends in the path of an actuating rod 35 whose lower end passes through a guide 36 secured to the lay sword 37 as seen on Fig. 1. Pivotally mounted on a bracket 38 secured to the loom frame is a lever 39, its pivotal point being located between the ends of the lever and the forward end thereof having a pin and slot connection with the actuating rod 35. The rearwardly extending end 40 of the lever bears against a cam 41 on the cam shaft 42. The cam 41 is a two lobe cam and the cam shaft 42 makes one revolution to each two revolutions of the crank shaft which operates the lay.

From the construction so far described it is apparent that the rod 30 will be moved lengthwise of the lay in one direction by the connection to the cam shaft 42. To move the rod 30 in the opposite direction and thereby give it reciprocatory movement I provide a spring 43 between a pair of collars 44, 45. Stops 46 and 47 are provided on bracket 33 to limit the movement of the rod 30 longitudinally of the lay.

Secured to the rod 30 is a cam member 48 having cam portions 49 and 50 with a notch 51

therebetween. Extending laterally of the axis of the center fork is a stop finger 52 which moves with the center fork. When the cam member 48 is moved longitudinally of the lay to the left (as viewed on Fig. 1), the stop finger 52 will ride along the inclined surfaces of the cams 49 and 50, thereby lifting the tines of the center fork to permit the shuttle to pass. As the rod 30 is moved to the right by the spring 43, the tines of the center fork will drop under the influence of gravity plus the spring 29 and if filling has been laid in the shed the tines will come to rest upon and be supported by the filling, however if filling is absent or breaks the tines will drop into a recess 52' on the lay, thereby causing the stop finger 52 to ride down the incline 50 and engage with the notch 51 and stop movement of the rod 30. When the movement of rod 30 is stopped by the center fork, in the above described manner the bunter 31 is properly positioned to actuate the revoking mechanism to revoke any existing call for transfer and the bunter 34 is properly positioned to actuate the loom stopping mechanism all as 25 will be more fully described hereinafter.

The loom stoppage mechanism actuated by the center fork mechanism may be similar to that shown and described in the aforementioned patent to Lindsjo. Such mechanism may include 30 a knock-off plunger 53 located on the breast beam and aligned to be engaged by the bunter 34 when the bunter is positioned to stop the loom by the center fork mechanism. The plunger 53 extends forwardly and is connected 35 at 54 with a knock-off lever 55, which is pivotally mounted on the breast beam with its opposite end bearing against the shipper 56. The result being that should the knock-off plunger 53 be moved forwardly by the bunter 34, the shipper will be detached from its holding notch and loom stoppage result.

The mechanism for revoking a call for transfer may comprise a projection 57 on the shuttle feeler 13. The projection 57 is in alignment with the bunter 31 when the movement of the rod 30 is stopped by the center fork. When the rocker shaft 7 is turned by the feeler mechanism to raise the latch 19 into position to call for transfer, the shuttle feeler 13 is also raised into position to feel the shuttle and see if the shuttle is properly positioned within the shuttle box. The projection 57 on the shuttle feeler will make contact with the bunter 31 and will be moved forwardly, thereby moving with it the latch 19 and preventing contact between latch 19 and the bunter 22 carried by the lay.

The operation of the device is as follows:

Assume the shuttle has just been picked along the lay from right to left and is in the left hand shuttle box as shown on Fig. 1. On the forward beat of the lay the feeler mechanism detects substantial exhaustion of the filling on the bobbin and through the mechanism of the transmitter 4 and actuator 5 the rocker shaft or starter rod 7 is turned, thereby raising the shuttle feeler 13 and latch 19 to operative position to call for a transfer on the next forward beat of the lay. Now, if as the shuttle is picked from left to right there is a failure of filling in the shed, the center fork will act to stop the loom, with the result that if nothing was done to revoke the call for transfer, only a partial transfer would take place before the loom came to rest. However, with the present invention, if as the shuttle is

picked from left to right there is a failure of filling in the shed the center fork through the stop finger 52 will stop the rod 30 from reciprocating and the rod 30 will be stopped with the bunter 34 properly positioned to actuate the stopping mechanism by engagement with knock-off plunger 53 on the forward beat of the lay. Also the bunter 31 will be properly positioned to engage the projection 51 on the shuttle feeler 13 on the forward beat of the lay whereby upon the forward beat of the lay the shuttle feeler will be moved forwardly, and with it the latch 19 thereby preventing engagement between latch 19 and the bunter 22 on the lay, or in other words revoking the call for transfer.

Having thus fully disclosed the preferred embodiment of my invention, I claim:

1. In a filling replenishing loom, the combination of a reciprocating lay, replenishing mechanism including a latch movable to position calling for replenishment of filling, a center fork stop motion including a filling fork, a reciprocating member mounted on said lay, means for reciprocating said member, said member having means intermediate its ends for raising said filling fork as said member reciprocates, means carried by said fork for arresting the movement of said member when said fork detects absence of filling in the shed, and means actuated by said member upon the forward beat of the lay, to move said latch to inoperative position when arrested in its movement, whereby any existing call for replenishment is revoked.

2. In a filling replenishing loom, the combination of, a reciprocating lay, replenishing mechanism including a latch movable to position calling for replenishment of filling, means for moving said latch to said position upon substantial exhaustion of filling in the shuttle, a center fork stop motion including a center fork, a reciprocating rod mounted on said lay and having means intermediate its ends for raising said center fork as said rod reciprocates, means for reciprocating said rod, means operated by said center fork for arresting the movement of said rod when said fork detects absence of filling in the shed, loom stopping means, and latch revoking means, said loom stopping means and said latch revoking means being actuated by said rod upon the forward beat of the lay when the rod is arrested in its movement as aforesaid, whereby said loom is stopped and any existing call for replenishment revoked upon detection of absence of filling by the center fork.

3. In a filling replenishing loom, the combination of a reciprocating lay, transfer mechanism including a latch, means actuated upon the substantial exhaustion of filling in the shuttle, to move said latch into a position to be engaged by the lay and thereby operate said transfer mechanism, a center fork, a member mounted on said lay for reciprocatory movement longitudinally thereof and having means intermediate its ends for raising said center fork as said member reciprocates, means for reciprocating said member, means operated by said center fork for arresting the movement of said member when said fork detects absence of filling in the shed, loom stopping means and latch revoking means, both said last named means being actuated by said member upon the forward beat of the lay when arrested in its movement whereby said loom is stopped and any existing call for operation of said transfer mechanism by said latch

is revoked upon detection of absence of filling by said center fork.

4. In a loom having a reciprocating lay, the combination of automatic replenishing mechanism including a latch movable to operative and inoperative positions, said latch when in operative position participating in the operation of said replenishing mechanism, a center fork stop motion comprising loom stopping mechanism, a reciprocatory member movable longitudinally of the lay and mounted thereon, means for reciprocating said member, said member having means adjacent one end positionable to actuate said loom stopping mechanism and also having means adjacent the other end positionable to move said latch to inoperative position, a center fork, means controlled by said center fork for stopping reciprocation of said member on detection of filling failure with said second named means in position to actuate said loom stopping mechanism upon the forward beat of the lay and said third named means in position to move said latch to inoperative position upon the forward beat of the lay whereby upon the forward beat of the lay said loom is stopped and said movement of said latch prevents operation of said transferring mechanism.

5. In a filling replenishing loom, the combination of a reciprocating lay, loom stopping mechanism, a breast beam, a filling feeler on said breast beam, a train of mechanism to initiate replenishment of filling under control of said filling feeler including a latch movable to operative and inoperative positions, said latch when in operative position actuating the replenishment mechanism on the forward beat of the lay, a center filling fork stop mechanism effective to stop said loom on the absence of filling in the shed, a sliding rod mounted on said lay for reciprocation longitudinally thereof, means for reciprocating said rod, a projection on each end of said rod, and means controlled by said center fork mechanism for positioning said rod upon absence of filling in said shed so that upon the forward beat of the lay one of said projections actuates said stopping mechanism for stopping the loom and the other projection moves said latch to the inoperative position thereby rendering said replenishing mechanism inoperative.

6. In a filling replenishing loom, the combination of a reciprocating lay, transferring mechanism including a latch movable to operative and inoperative positions, said latch when in operative position participating in the actuation of said transferring mechanism by said lay, feeler mechanism operable upon substantial exhaustion of the filling to move said latch to operative position, loom stopping means including a filling fork mechanism for actuating said stopping means upon the absence of filling in the shed, said filling fork mechanism including a slidable member mounted on said lay and movable into position for actuating said loom stopping means upon the forward beat of the lay, means for moving said member, and means carried by said slidale member and operable when said slidale member is moved to loom stopping position to move said latch to inoperative position upon the forward beat of the lay thereby preventing actuation of said transferring mechanism.

7. In a filling replenishing loom, the combination of a reciprocating lay, a center fork mounted on the lay, a bunter pivotally connected to the lay for swinging movement longitudinally

thereof, a cam shaft having a cam for causing movement of the bunter about its pivotal connection with the lay in one direction longitudinally thereof, a spring for moving the bunter longitudinally of the lay in the opposite direction, a rod connected to the bunter for movement thereby, a cam device connected to the rod for raising the center fork as the bunter is swung about its pivot by its actuating cam and a locking notch formed in the cam device, an arm actuated by the center fork for engagement with said locking notch when the center fork detects absence of filling in the shed, a knock-off plunger actuated by the bunter upon the forward beat of the lay to stop the loom when the bunter is arrested in its movement and means actuated by said rod upon the forward beat of the lay to revoke any existing call for operation of the replenishing mechanism when the rod is arrested in its movement.

8. In a filling replenishing loom, the combination of a reciprocating lay, replenishing mechanism including a latch movable to position calling for replenishment of filling upon substantial exhaustion of filling in the shuttle, a center fork stop motion comprising a reciprocatory rod mounted upon said lay for movement longitudinally thereof and having a bunter adjacent each end, means for reciprocating said rod, a cam device connected to the rod for raising the center fork as the rod reciprocates, a locking notch formed in the cam device, an arm actuated by the center fork for engagement with said locking notch when the center fork detects absence of filling in the shed, a knock-off plunger actuated by one of said bunters upon the forward beat of the lay to stop the loom when said rod is arrested

in its movement and means actuated by the other of said bunters upon the forward beat of the lay to move said latch to inoperative position when said rod is arrested in its movement thereby revoking any existing call for replenishment.

9. In an automatic replenishing loom, the combination of a reciprocating lay, replenishing mechanism including a latch movable from inoperative to operative position, means for moving said latch to operative position upon substantial exhaustion of filling in the shuttle, said latch when in operative position calling for and participating in the operation of said replenishing mechanism and a center fork stop motion comprising loom stopping mechanism, a reciprocating member mounted on said lay and movable longitudinally thereof, means for reciprocating said member, said member having means adjacent one end positionable to actuate said loom stopping mechanism upon the forward beat of the lay and means adjacent the other end positionable to revoke the call of said latch for operation of said replenishing mechanism by moving said latch to inoperative position upon the forward beat of the lay, said third named means being in revoking position when said second named means is in loom stopping position, a center fork for detecting filling failure and operable upon detection of filling failure to stop said reciprocating member with said second named means in position to actuate said loom stopping mechanism upon the forward beat of the lay, whereby after said center fork has acted to stop said loom any existing call for operation of said replenishing mechanism is revoked.

CARL D. BROWN.
